UNITED STATES PATENT OFFICE

WILLIAM O. BARRY, OF COLUMBUS, OHIO

DESIGN FOR A GLASS TUMBLER

Application filed June 3, 1932. Serial No. 43,968. Term of patent 14 years.

To all whom it may concern:

Be it known that I, WILLIAM O. BARRY, a citizen of the United States of America, residing at Columbus, in the county of Franklin and State of Ohio, have invented a new, original, and ornamental Design for a Glass Tumbler, of which the following is the specification, reference being had to the accompanying drawing forming a part thereof.

The figure is a perspective view of a glass tumbler, showing my new design.

The rings shown on the tumbler are fused

on the outside surface of the tumbler. These rings are in color, different from the color of the tumbler. Any color may be used for these rings. One color may be used for all the rings on the same tumbler, or rings of different colors may be used on the same tumbler. The same surface ornamentation may be applied to similar articles.

I claim:

The ornamental design for a glass tumbler, substantially as shown and described.

WILLIAM O. BARRY.
